UNITED STATES PATENT OFFICE.

FRANK J. DURDA, OF ROBSTOWN, TEXAS.

ROAD-BUILDING MACHINE.

Application filed November 12, 1923. Serial No. 674,247.

This invention relates to a machine used in the construction of concrete or asphalt roads and has more particular reference to a machine that includes strike-off and tamping elements, the primary object thereof being the provision of such a machine wherein these strike-off and tamping elements are operated in a more simple and effective manner than are the similar elements employed in machines now upon the market and this without requiring a great amount of power.

One of the main objects of this invention is to provide a road constructing machine wherein the same is adapted to be moved slowly in opposite directions as desired upon track-ways provided at opposite sides of the road, this machine moving mechanism being controlled by the motor power that is employed in the operation of the before mentioned strike-off and tamping elements.

Yet another object of the invention is to provide a machine of the above character wherein means is provided for preventing a reversal of movement of the machine when the same is working up hill.

A still further object is to provide a road constructing machine wherein the same is comparatively speaking, so simple of construction and operation as to be operated by even unskilled laborers.

With the above general objects in view, and others that will become apparent as the nature of the invention is better understood, the same comprises the novel form, combination and arrangement of parts hereinafter more fully described, shown in the accompanying drawings and claimed.

In the drawings wherein there is shown the most practical embodiment of the invention with which I am at this time familiar, and wherein like reference characters indicate corresponding parts throughout the different views,

Figure 1 is a top plan view of one end of a road constructing machine constructed in accordance with the present invention,

Figure 1^a is a similar view of the other end of the machine,

Figure 2 is an elevational view of one end of my improved machine,

Figure 3 is an enlarged fragmentary inside elevational view of a portion of the machine for disclosing in side elevation one of the rear traction wheels therefor,

Figure 4 is an enlarged detail sectional view taken through Figure 3 for disclosing

in side elevation, the manually operable means whereby the movements of the machine upon its track rails in reverse directions may be controlled,

Figure 5 is an enlarged detail vertical cross section through the mechanism shown in Figures 3 and 4,

Figure 6 is an enlarged detail side elevational view of the supporting and raising mechanism for the template or strike-off bar of the present machine,

Figure 7 is a longitudinal sectional view taken through Figure 6,

Figure 8 is an enlarged perspective of the roller carrying plate element that forms a salient part of said supporting and raising mechanism for said template or strike-off bar,

Figure 9 is a detail sectional view taken substantially upon the line 9—9 of Figure 6 and looking in the general direction of the arrows of said Figure 6,

Figure 10 is an elevational view of one side of one of the drum members that co-operate with other elements of the rear traction wheels of the machine together with the power means thereof for causing rotation of these wheels in opposite directions as desired,

Figure 11 is an enlarged detail side elevational view of one of the rear traction wheels of the machine for more clearly disclosing the means for preventing a reversal of movement of the machine when the same is working upon a hill,

Figure 12 is an enlarged elevational view of one side of a dog member that co-operates with a ratchet wheel carried by the respective traction wheel of the machine for preventing said reversal of movement of the machine, and

Figure 13 is a similar view of a connecting element between said dog and a control lever employed for disengaging said dog from the ratchet wheel for allowing reversal of movement of the machine when desired.

Now having particular reference to the drawing, my novel machine embodies a supporting frame that includes a pair of spaced parallel U-bars 5 connected at their opposite ends by relatively long I-beams 6, said U-bars 5 being also interconnected intermediate their ends by brace bars 7, Figures 1 and 1^a. At opposite ends of the connecting I-beams 6 are pendant relatively inverted U-shaped shaft hangers 8 extending through

which are front and rear axle shafts 9—9 and 10—10, respectively and freely rotatable upon which are front and rear flanged supporting wheels 11—11 and 12—12, respectively. These supporting wheels have rolling engagement with channel rails 13 at opposite sides of the road being constructed, it being preferable that these rails serve as the forms for the road being constructed.

10 Intermediate the ends of the spaced parallel frame bars 5 is a platform 14 upon which is to be supported any desirable form of power plant, not shown, and preferably of the internal combustion engine type the power shaft 15 of which is adapted to be clutched to and unclutched from a horizontal propeller shaft 16 suitably journaled at its opposite ends within bearings 17 through the medium of a desirable form of 15 clutch mechanism 18, Figure 1. Traversing the parallel frame bars 5—5 of the machine frame and suitably journaled at its opposite ends within said frame bar is a rock shaft 19 that is operatively connected to the movable element of the clutch mechanism 18 and that is also operatively connected to one 20 end of a relatively long connecting rod 20 that extends laterally toward one side of the machine and is in turn connected at its opposite end to a hand lever 21 pivoted at its lower end to the adjacent I-beam 6 of the machine frame whereby said shaft 19 may be rocked in reverse direction for controlling the clutch mechanism 18.

25 Keyed to this propeller shaft 16 at points adjacent the opposite ends thereof are cam elements 22, Figure 4, with which are associated the front ends of forwardly extending pitman rods 23 and that are in turn 30 pivotally connected at their opposite ends between upstanding ears or lugs 24 formed upon the top side of drums 25 of a cross sectional configuration as more clearly shown in Figure 5, said drums 25 adapted for movements in opposite directions upon 35 the rear axles 10 of the machine and this inwardly of the traction wheels 12—12 thereof.

40 As more clearly shown in Figure 5 each of the rear supporting and traction wheels 12 is formed upon its inner side with a circular rim 26 which engages within the inner open side of the adjacent before mentioned drum 25 said drum being formed 45 inwardly of its open end and with a guide flange 27.

46 Operatively connected to each of the supporting and traction wheels 12 and within the respective drum 25 is a pair of ratchet 50 wheels designated respectively 28 and 29 the teeth of which are inclined in opposite directions and complementary with each of which is a spring-pressed dog 28' and 29' respectively. As more clearly shown in 55 Figure 4 said dogs are normally maintained

in engagement with their respective ratchet wheels through the medium of expandable coiled springs 30. For selective engagement with the inner shouldered ends 31 of said dogs is a cross lug 32 that is carried 60 by the inner pivoted end of lever 33 pivoted in the respective drum and adapted for swinging movement in a slot 34 provided for this purpose.

65 Formed integrally upon the outer side 70 of each of said drums 25 is a segment 35 formed with a pair of spaced notches 36 for the selective reception of a spring detent 37 carried by said handle 33 it being of course obvious that when the dogs 28—28' 80 are in engagement with their respective ratchet wheels 28—28 of the rear supporting and traction wheels 12—12 and when the propeller shaft 16 is rotating, a relatively slow forward movement of the machine 85 will be had. By disengaging said dogs 28—28' from their respective ratchet wheels and engaging the other pair of dogs 29—29' with their respective ratchet wheels 29—29 a rotation of said propeller shaft 16 90 will manifestly control the slow movement of the machine in an opposite direction upon the rails 13.

95 As a means for preventing the reversal of movement of the machine when the same is working upon inclined roads each of said rear supporting and traction wheels 12 is equipped upon its outer face with a ratchet wheel 38 the teeth of which are inclined in a rearward direction as more clearly shown 100 in Figure 11. Extending through a circular opening in the outer leg portion of each of the rear wheel shaft hangers 8 is a relatively long bolt 39, Figure 5, upon the inner end of which is a dog 40 complementary to the 105 respective ratchet wheel 38, the outer face of this dog at its rear end being formed with a pair of diametrically disposed dove-tail shaped lugs 41. Upon the respective bolts 39 outwardly of the dog 40 is a disk 110 42, the inner face of which is formed with a pair of diametrically opposite dove-tail shaped lugs 43 the lengths of which are slightly lesser than the space between the pair of dove-tail shaped lugs 41 of said dog 115 40 for consequently allowing a slight movement of the dog with respect to the disk.

120 Operatively connected to the outer end of each of said relatively long bolts 39 is a hand lever 44 that carries a suitable form of 125 spring controlled detent 45 for co-operation with spaced notches 46 in a segment 47 rigidly connected to the adjacent leg of the respective hanger 8. From a consideration of Figure 11 it will be noted that each of 130 said dogs 40 is normally maintained in engagement with its respective ratchet wheel through the medium of an expandable coiled spring 47 and that when the hand lever 44 is in the position shown in said Figure 11 130

the supporting and traction wheels 12—12 will be allowed to rotate in a forward direction through the transmission mechanism between the propeller shaft 16 of the machine and said traction wheels. However, in view of the structure just set forth a reversal of movement of said traction wheels 12—12 will be prevented when my machine is working up hill. However, should a reversal of movement of the machine be desired the detent 45 may be removed from the notch shown and the hand levers at opposite sides of the machine swung rearwardly for consequently raising the dogs 40 from their complementary ratchet wheels 38. Slightly rearwardly of the front horizontal frame bar 5 of the machine and extending parallel therewith is a shaft 49 journaled at its opposite ends within the end frame bars 6—6 of the machine frame and also being disposed for rotation within registering openings in the strengthening bars 7 between said parallel horizontal frame bars 5—5. Keyed to this shaft 49 adjacent its opposite ends are pinion gears 50, Figure 9, the teeth of which have mesh with rack teeth 51 upon the upper ends of pendant flat-like bars 52 slidable at their lower ends in guide bars or trams 53, Figure 2, which guide bars are pendant from a suitable under structure 54, supported from the frame of the machine. Each of these rack bars 52 carries at its lower end a relatively long and peculiarly shaped cross plate 54 that carries at its opposite ends pairs of forwardly extending spaced rollers 55, Figure 6 between which extends the upper flanged portion 56' of a horizontal U-beam 56 upon the front side of which is removably secured a concrete strike-off template 57, a number of these templates being provided for selective attachment to said U-beam 56 whereby the desired crown of the road may be had, it being of course understood that said templates are formed with curvatures of varying degrees.

In engagement with the outer face of the template 57 is a guide roller 58 suitably carried by the under frame structure 54 above described while in rolling engagement with the inner side of the U-beam 56 is another guide roller 59 these guide rollers co-operating with said guide members 53 for preventing any forward or rearward thrust of the U-beam and templet 56 and 57 respectively.

One end of the before mentioned horizontal shaft 49 extends beyond the adjacent I-beam 6 of the machine frame and is equipped with a ratchet wheel 60, Figure 6, complementary with which is a pivoted dog 61 for manifestly preventing a reversal of movement of said shaft 49. This end of the shaft is squared at 62 for the reception of a handle, it being apparent that when said

shaft 49 is manually rotated in one direction the rack bars 52 will be consequently raised for raising the template carrying U-beam to the desired height or for raising the same in an upward direction to the limit 70 of its movement whereby the machine may be moved over the road without said template 57 engaging the surface of the roadway.

The before mentioned propeller shaft 16 is 75 equipped at one side of the clutch mechanism 18 with a relatively small beveled gear 63 that has mesh with a relatively larger beveled gear 64 upon the inner end of a crank shaft 65 which crank shaft is, as 80 shown more clearly in Figure 1, journaled at its opposite ends within the foremost horizontal frame bar 5 of the machine frame and an auxiliary bar 66 between adjacent strengthening bars 7 of the machine frame. 85

Between the cranked portion of said shaft 65 and the U-beam 56 of the strike-off mechanism of the machine, is a connecting rod 67 it being obvious that when the crank shaft 65 is rotated a rectilinear movement 90 will be imparted to said U-beam 56 of the strike-off mechanism for consequently striking off the concrete to the proper grade and curve, and this while the machinery is moving slowly forwardly. 95

Adjacent the opposite ends of the propeller shaft 16 are beveled gears 68 that have mesh with other beveled gears 69 upon the inner ends of crank shafts 70 journaled in a manner similar to the before mentioned 100 crank shaft 65. Pendant from the crank portions of these shafts 70 are connecting rods 71 that are resiliently connected as at 72, Figure 2, to a tamping element 73 which tamping element is suitably guided for vertical movements in opposite directions as indicated generally at 74. 105

Referring now to the general operation of my apparatus, it will be seen and understood that, as the apparatus advances along 110 the rails, to the sides of the paving-bed, this movement will be of an intermittent nature caused by the rotation of the propeller shaft 16 which rotates elements 22 to move pitman rods 23 back and forth, thereby oscillating drums 25 and through either pawls 28' or 29' impart intermittent rotation of ratchets 28 and wheels 12. The direction of the intermittent rotation of these wheels 12 may obviously be reversed by 115 proper manipulation of lever 33 as heretofore explained in detail. The strike-off mechanism is brought into play when desired by releasing pawl 61 and the horizontal U-beam 56 will lower of its own weight to 120 engage the strike-off templates 57 with the paving bed. The shaft 16 imparts rectilinear motion to the U-beam and strike-off templates attached thereto through gears 63 and 64, crank shaft 65 and pitman 67 so 125 130

that the paving material is spread to produce the desired crown. Obviously, a hand crank may be engaged on the squared end of the shaft 49 to rotate the same to operate gears 50 and rack bars 52 to raise the strike-off mechanism clear of the road when desired. The rotation of the shaft 16 also simultaneously causes the rotation of crank shafts 70 through gears 68 and 69 and these crank shafts raise and lower connecting rods 71 and tamping elements 73 for tamping the paving bed.

It will thus be seen that I have provided a highly novel and efficient form of road constructing machine and one that may be effectively employed in the striking off and tamping operations of the road material.

The detailed operation as well as numerous advantages of a machine of this character will be readily apparent to those skilled in the art, and even though I have herein set forth the most practical embodiment of the invention with which I am at this time familiar, it is nevertheless to be understood that minor changes may be made within the invention without departing from the spirit and scope of the appended claims.

Having thus described my invention, what I claim as new and desire to secure by Letters Patent is:—

1. In a road building machine, a wheeled frame, a shaft journaled transversely of the frame, a plurality of gears keyed to the shaft, a plurality of vertically extending rack bars meshing with the gears, guide means for the rack bars, a plate carried by each rack bar, rollers journaled on each plate, a beam having a flange disposed between the rollers so as to be slidably mounted on the rack bars, means for reciprocating the beam, means for preventing the shaft from rotating in one direction, and a plurality of templates mounted on the beam. 35

2. In a road building machine, a wheeled frame, a shaft journaled across the frame, 45 gears on the shaft, vertically disposed rack bars meshing with the gears, guide means for the rack bars, a plate mounted on each rack bar, a pair of rollers on each plate one above the other, a beam having a flange receivable between the rollers, templates mounted on the beam, a crank shaft journaled in the frame, means for rotating the crank shaft, and a pitman connecting the crank of the crank shaft with the beam for 50 imparting rectilinear movement thereto.

In testimony whereof I affix my signature.

FRANK J. DURDA.
